P. FISCH,

PUMP FOR DELIVERING MOTOR FUEL AND THE LIKE.
APPLICATION FILED NOV. 15, 1920.

1,418,293.

Patented June 6, 1922.

FIG. 2

Inventor: Paul Frisch.
Attorney: Alfred E. Alderson

UNITED STATES PATENT OFFICE.

PAUL FISCH, OF LYON, FRANCE.

PUMP FOR DELIVERING MOTOR FUEL AND THE LIKE.

1,418,293.

Specification of Letters Patent. Patented June 6, 1922.

Application filed November 15, 1920. Serial No. 424,248.

To all whom it may concern:

Be it known that I, PAUL FISCH, of Lyon, France, a citizen of the French Republic, have invented certain new and useful Improvements in Pumps for Delivering Motor Fuel and the like, of which the following is a specification.

This invention relates to improvements in pumps for delivering motor fuel and the like, used for feeding fuel for the engines of motor cars, the following difficulties have hitherto been present:

1. Insufficient tightness for petrol and other volatile liquids of the joints or stuffing boxes on members in movement (axles in particular).

2. Oiling of parts in frictional contact rendered difficult by the presence of the petrol.

3. Necessity of actuating the pump by belt or other gearing resulting in complication of construction, mounting, and high cost of production.

The type of pump forming the object of the invention does not comprise any joint on a movable part, as the pump is arranged entirely inside the fuel tank, which renders unnecessary all tightness. It does not require any oiling or any motor actuation.

The invention consists in principle in utilizing for pumping petrol or other volatile liquids, the relative movements of a member of any kind fixed to a non-suspended part of a vehicle, for example, the back or front axle with respect to the suspended vehicle, of which the fuel tank forms part, these movements being transmitted to the pump proper.

An example of construction of the invention is illustrated in the annexed drawings, in which:

Fig. 1 is a vertical section through the axis of the pump.

Fig. 2 is a diagram illustrating the arrangement of the device at the back of the vehicle.

The body of the pump is formed by a suitable cylinder of metal in which the body of the pump proper *b* is bored parallel and eccentric to the axis of said cylinder.

In the maximum thickness of the walls of the body of the pump and parallel to the axis is bored the feed channel *c*. The upper part of the body of the pump is closed by a

wall having a central opening *d* for the passage of the piston rod *e*, and is also provided with a threaded union *f* in extension of the channel *c*, and on which the feed pipe is mounted. The pump body is screw threaded outside at *g* in order that it can be screwed into a union *l* in the top of the fuel tank *r* in such a way that the body of the pump projects into this reservoir to within a slight distance from the bottom.

Further, the inner surface of the lower end of the body *b* is screw threaded to receive a stopper *i*, provided inside with a tube *i'* comprising a seat for a ball *q* or valve of any kind provided with a spring or not.

The interior of the body *b* is in communication with the feed tube *c* by an opening *j*, and on the other hand it is in communication with the fuel tank along the whole of the part situated above the highest point of the stroke of the piston *m* by a series of openings such as *k*.

The feed tube *c* comprises a suitable seat intended to receive a ball *u* or a spring or other valve of any kind. This valve as well as the valve *q* are arranged to assure the circulation of the fuel in a suitable direction.

In the body of the pump is a sliding piston *m* fixed at the end of the vertical rod *e*, the upper end of which is provided with a head *s* provided with a biconical hole *s'*. This rod *e* carries besides, at a suitable height in the interior of the body of the pump, a disk *n* intended to guide and support the rod. A bracket *o* supporting the shaft *p* of the actuating member is fixed on the top of the body of the pump.

The pump is actuated by any suitable mechanical connection between the point chosen of the parts not suspended of the vehicle and the upper part of the rod *e* of the piston *m*.

In particular to prevent too sudden movements elastic transmission means of any suitable kind can be employed. Fig. 2 shows an example of such means.

On one of the bearing blocks of the rear axle of the vehicle is mounted a collar *w* on which is fixed a pin *a*, the free end of which is provided with a head *a'* provided with a biconical hole in which is engaged one of the ends of a plate spring *r* oscillating on the shaft *p*, rotatable freely at the extremity

of the bracket *o*. The other end of the spring *r* is engaged in the hole *s'* in the head *s* of the piston rod *e*.

The action is easily understood.

5 When the vehicle is running the back axle takes a succession of vertical movements of very varying amplitude and these movements are transmitted to the rod *a* and to the spring plate *r*.

10 The fuel reservoir *y* being integral with the frame of the car and the body of the pump being fixed in this reservoir, it follows that the spring *r* oscillates round the fixed point *p* and that its movements of oscillation are transmitted to the rod *e* which in consequence effects alternately rising and falling vertical movements.

15 The rise of the piston causes the suction of the fuel from the tank into the pump body *b*; its descent causes the expulsion of the fuel into the channel *c*. The piston has no need to be absolutely tight and does not require packings, its cylindrical surface is provided with annular grooves to lessen the 20 loss of charge. The lack of tightness is translated into a diminution of feed which has no inconvenience in this case as the feed required is generally small and the amplitude of the movements as well as their frequency will always produce an amply sufficient feed.

The arrangement of details would vary according to the particular application of the invention.

What I claim as my invention and desire 35 to secure by Letters Patent of the United States is:—

A pump for supplying fuel for the engines of motor vehicles, comprising a fuel tank mounted on a suspended part of the 40 motor vehicle, a vertical pump body mounted in the top of said tank and extending downwardly therein and having orifices in its wall communicating with said tank, a piston movable in said pump body, a rod 45 attached to said piston, means for guiding said piston, a delivery conduit in communication with the lower end of said pump body and leading to the point of consumption of said fuel, a valve at the point of junction 50 of said conduit with said body, an inlet valve at the base of said body and means for actuating said piston connected to a non-suspended part of the vehicle, and operated by the relative movements of the suspended 55 and non-suspended parts of the vehicle.

In witness whereof I have signed this specification in the presence of two witnesses.

PAUL FISCH.
